UNITED STATES PATENT OFFICE.

LAURA C. SCHUTTE, OF HILLAND, SOUTH DAKOTA.

CUFF-LINK.

1,271,089.

Specification of Letters Patent.

Patented July 2, 1918.

Application filed January 4, 1918. Serial No. 210,330.

To all whom it may concern:

Be it known that I, LAURA C. SCHUTTE, a citizen of the United States, residing at Hilland, in the county of Haakon and State 5 of South Dakota have invented certain new and useful Improvements in Cuff-Links, of which the following is a specification.

My invention relates to cuff links and the principal object thereof is to provide a cuff link which is durable and which may be formed from a single length of material, such as celluloid, gold, etc.

The second object of the invention is to provide a fastener of the above mentioned 15 character which will effectively fasten the ends of the cuff together and which may be readily engaged and disengaged therefrom.

Another object of my invention is to provide a cuff link which is simple in construction, 20 is inexpensive to manufacture, and which may be placed on the market at a minimum cost.

The above and other objects will be fully set forth in the following specification and 25 the inventive features will be explicitly defined in the appended claims.

The invention consists in the forms, arrangements, and details which will be hereinafter specifically referred to and illustrated 30 in the accompanying drawings, in which:—

Figure 1 is a side elevation of a cuff having my improved link applied thereto,

Fig. 2 is a view taken at the right hand 35 or outer edge of the cuff,

Fig. 3 is a longitudinal sectional view taken on the line 3—3 of Fig. 1, and

Fig. 4 is a perspective of my improved link.

Like characters of reference indicate like 40 parts in all the views.

Referring to the drawings in detail, the numeral 5 designates a cuff which is one of the usual type.

However, the button holes in this cuff 45 are formed differently than the conventional button hole.

In lieu of the conventional button hole, I provide a pair of parallel alined spaced slots 50 6 in each of the longitudinal edges of the cuff.

My improved button is formed from a flat blank of resilient material which is extended to provide a rectangular head 7 and 55 bent transversely intermediately its ends as designated at 8 and extended reversely and

at an incline and thence bent again transversely as at 9 and extended reversely again or toward the bend 8 and at an incline. This latter portion constitutes a tongue. 60 That portion of the length of material between the bends 8 and 9 is provided with a slot 10 which is disposed near and extended transversely of the bend 9 and is adapted to receive the tongue when the link is in operative position as is clearly shown in Fig. 3. The longitudinal edges of the tongue and that portion of the blank between the bends 8 and 9 are beveled as illustrated in Fig. 4.

In securing the cuff together, the tongue 70 of my improved cuff link is inserted through the slots 6 in the cuff as shown in Fig. 3 and then engaged with the slot 10. It will be seen that when the parts are thus assembled it will be impossible for the ends 75 of the cuff to become separated. It will also be seen that the cuff link of this character will not be easily lost as is the case with cuff links of the conventional type. The head 8 which is adapted to be worn 80 upon the right hand side of the cuff also affords a surface for suitable initials.

From the above disclosure, it will be seen that I have provided a simple and efficient cuff link which may be manufactured and 85 sold at a minimum cost.

This embodiment of the invention is clearly illustrated and it is to be understood that the invention can be modified in many different respects, that may be fully embodied in the scope of the appended claims. 90

What is claimed, is:—

1. A cuff link formed from a length of sheet material bent intermediate its ends and extended reversely and thence bent 95 again and again extended reversely to afford a tongue, and means for securing the tongue to the first reversely extending portion.

2. A cuff link formed from a length of 100 sheet material bent intermediate its ends and extended reversely and thence bent again and again extended reversely to afford a tongue, and means for securing the tongue to the first reversely extending portion, said 105 tongue having its longitudinal edges beveled.

3. A cuff link formed from a length of sheet material extended to provide a head and thence bent transversely and extended 110 reversely at an incline, said length being thence bent transversely and extended re-

versely again to afford a tongue, the first reversely extending portion being provided with a slot adapted to accommodate the tongue.

5 4. The combination with a cuff having spaced aligned slots at its longitudinal edges; of a cuff link formed from a length of material bent upon itself intermediate its ends and extended reversely and thence bent 10 again transversely and extended reversely

to afford a tongue adapted for reception in the slots in the cuff, the first reversely extending portion being provided with a slot adapted to receive the tongue.

In testimony whereof I affix my signature 15 in presence of two witnesses.

LAURA C. SCHUTTE.
